UNITED STATES PATENT OFFICE.

GRACE CORRY, OF NEW YORK, N. Y.

DESIGN FOR A DOLL.

55,594.

Specification for Design.

Patented July 6, 1920.

Application filed March 29, 1920. Serial No. 369,756. Term of patent 3½ years.

To all whom it may concern:

Be it known that I, GRACE CORRY, a citizen of the United States of America, residing at New York city, county and State of New York, have invented a new, original, and ornamental Design for a Doll, of which the following is a specification, reference being had to the accompanying drawing, forming part hereof, which illustrates a perspective view of a doll embodying my new design.

I claim:—

The ornamental design for a doll, as shown.

Signed at New York city, N. Y., this 23rd day of March, 1920.

GRACE CORRY.

Witnesses:

EDWARD A. JARVIS,
MAURICE BLOCK.
